DELMAR LEWIS JOHNSON, OF ST. LOUIS, MISSOURI

FOLDING FURNITURE

Application filed May 3, 1930. Serial No. 449,451.

This invention relates to improvements in folding furniture, particularly to an article of furniture of improved adaptation as a table for shower-bathing and dressing infants.

5 The present invention constitutes a continuation, in part, of an application filed by me on April 26, 1929, and bearing Serial Number 358,300. The present disclosure embodies the major elements and features shown and described in the former application, as well as certain improvements over the original subject matter.

15 The object of the invention may be stated generally as that of providing a novel and convenient support for infants while being bathed, rinsed and dressed, the support being of such a nature as to minimize the effort incident to lifting and moving an infant between the different stages or steps of the completed process.

20 A further object is to provide a supporting structure for the purposes noted, and constructed of companion portions rotatable relative to each other to bring the support from a substantially flat, folded assembly, into normal position of use, and vice versa.

25 A still further object of the invention is to provide a table or support having the characteristics heretofore enumerated, and in which the element immediately supporting the infant is of a flexible, readily replaceable and washable material, and so formed as to provide for drainage facilities whereby the support may be employed for the purpose of shower-bathing children, and thereafter, through the agency of a waterproof covering for the support, serve as a table or bench for drying and dressing purposes.

30 Still another object of my invention is to provide an improved folding table for the purposes noted, and which is characterized by a single leg structure so formed that the device may be used as a support auxiliary to the usual bath tubs of adult size, and sup-

ported thereby at a convenient working height so as to eliminate bending or stooping while bathing and dressing children, with the aid of the device.

35 A still further object may be noted as the provision, in combination with the flexible supporting element or cover noted above, of a pocket-forming portion adapted to contain, for easy access, all or a number of the accessory materials incident to the bathing and dressing of small children.

40 Further objects and advantages of the invention will appear as the description proceeds, and from the accompanying drawings forming a part of the present disclosure, and in which:

45 Fig. 1 is an elevation in perspective of the shower and dressing table as normally set up for use, and supported partially by and above a bath tub of usual type; Fig. 2 is a side elevation of the table as compactly folded for storage when not in use; Fig. 3 is an end elevation of the device as positioned for use; and Fig. 4 is an elevational detail of the clamping device employed in positioning the table for use.

50 It will be understood that the following description is more or less specifically detailed to the disclosure appearing in the present drawings, and is to be understood in a descriptive rather than a limiting sense. Obvious changes in the choice of material employed, the elements forming the various parts of structure described, as well as in the arrangement of the parts, may be made without departing from the spirit and full intended scope of the invention.

55 Referring now by reference numerals to the drawings, the table, or supporting portion of the structure, consists of a frame constituted by a pair of end rails 5 and 6 constructed preferably of wood and correspondingly socketed on their inner faces to receive a pair of side rails 7 and 8. The side rails are preferably of circular cross section, for pur-

poses hereinafter appearing, and may be glued as by waterproof glue, or otherwise secured into the appropriate sockets therefor in the rails 5 and 6. Also extending between the end rails 5 and 6, on the side most remote from the operator, is an auxiliary brace rail 9 which serves endwise to strengthen the rails 5 and 6, the brace rail extending between their free ends which project inwardly beyond the supporting surface proper as will appear, and serve normally as horizontal leg portions.

The supporting surface is, by preference, formed of a canvas cover 10, or like washable flexible material, and which, by further preference, is secured only at its sides. The innermost side of the canvas cover is secured to the round side rail 8, and extends transversely of the table, toward the operator and into engagement with the rail 7. The rails 7 and 8, to the end of engaging and stretching the canvas cover 10, are provided with a plurality of fasteners 11, in register with each of which is a gromet 12 in the cover. It is preferred to construct the fasteners 11, as well as the gromets, of such metal, or so plated, as to be rendered rust proof.

Intermediate the sides and ends of the cover 10 are a plurality of apertures 13, for purpose of drainage as the infant is being washed, shower-bathed or rinsed. The apertures 13 are, by preference, provided with gromets 14 so as to prevent any tendency of the fabric to unravel where it is perforated. If desired, the end portions of the canvas cover may be provided with a pair or more of apertures provided with gromets as shown at 15, for the purpose of inserting a draw string or the equivalent for keeping the canvas cover taut, as it may tend to loosen under the influence of repeated use and application of moisture.

As will hereinafter more fully appear from the description and use of the present table, it is my preference to provide an auxiliary cover 16, which in the present instance would be constructed of rectangular shape and correspond substantially to the effective area of the cover 10. The cover 16 is, by preference, formed of a water tight or waterproof, non-absorbent material such as rubber sheeting, and may be secured in place as by glove fasteners 17, there being one of such fasteners disposed at each corner of the working surface of the cover 10.

Depending from and, by preference, forming a part of the cover 10, is an overhanging or tab portion 18 presented laterally so as to hang vertically on the side of the table nearest the operator. This tab portion may be formed of such width and length as to be folded upon itself, the folds being sewed to the main body of the tab in a manner to form a plurality of pockets 19, each shown as opening at the top and affording convenient re-

ceptacles for a shower nozzle attachment, sponges, soap, and other bathing and dressing accessories.

Adapted for use as may be desired, for example as towel racks or handles by which to support the table when setting it up, there are provided, one on each of the end rails 5 and 6, U-shaped extensions 20 and 21. These members are, by preference, formed of metal and, like other metal parts of the structure, preferably formed or processed to resist rusting. It will readily appear that the auxiliary brace rail 9 may also be employed for lifting purposes, or as a rack for garments, towels and the like.

The description thus far has related to the horizontal supporting portion of the structure by way of describing its component parts. The sub-structure consists of a pair of legs of substantially A shape, each of which is pivotally secured at its upper end to one of the end rails 5 or 6 as by a through pin 24, this pivot being disposed by preference substantially nearer the operator's side of the table. The opposite, or lower ends of the legs 22 and 23 are shown as bifurcated, being arcuately recessed to correspond in curvature to, and for the purpose of engaging, the longitudinal hand rail of bath tubs of usual type and proportions. It will be seen that the legs 22 and 23 thus engage the opposite sides of the hand rail of the tub in a manner effectively to prevent movement of the table structure laterally or transversely of the tub when employed therewith. Extending lengthwise of the table and between the lower portions of the legs 22 and 23 is a brace 25, preferably of circular section and having at each end a shoulder (not shown) to receive at a point just inside of each of the legs 22 and 23, strut members 26 and 27, one at each end of the table.

The struts are adapted to extend inwardly across the tub and upwardly therefrom (Figs. 1 and 3) to engage in supporting relation the inner ends of the rails 5 and 6. For this purpose and to enable selectively locating the point of connection between the struts 26 and 27 and rails 5 and 6, I have provided at the outer end of each strut a pivotally supported clamp, consisting of a pair of clamping jaws normally resiliently urged toward open position, and adapted to be actuated toward closed position by a lever-operated cam pivoted to the outermost clamping jaw, all of which will clearly appear from Fig. 4. One of such clamping devices is shown generally at 28. For engagement by the clamps, each of the rails 5 and 6 is provided, as an extension from its under surface, a beaded portion 30 which may be formed as an integral part of each rail, or made separately and secured thereto.

For purposes of assembling and strengthening the supporting structure endwise and

transversely, the brace 25 may extend through a suitable aperture in each of the legs 22 and 23, a washer 31 and a wood screw 32 appearing on the outer face of each of the legs 22 and 23, and the wood screw being taken into the end section of the brace 25 at each end. The rigidity of the leg structure, particularly the portion constituted by struts 26 and 27, may be increased by employing an auxiliary brace 33 extending lengthwise of the structure and between substantially intermediate portions of the struts 26 and 27.

As will appear from Fig. 1, the dressing and shower table of the present invention is adapted for primary support on the outermost longitudinal hand rail of the usual bath tub of adult size, auxiliary support being derived by abutting and frictional engagement of the free extremities of rails 5 and 6, with a substantially vertical wall surface. It is of course desirable to enhance the frictional engagement at these points as far as practical. To this end and to avoid any tendency to mar the wall surface, I provide friction elements 34, formed say of rubber, and which may be secured as by a wood screw directly to the ends of the rails 5 and 6.

The manner of folding the described table from its normal position of use, and vice versa, the operation of extending it for use from its folded position, are thought to be fully apparent from the preceding description of parts and their relation, but may be briefly referred to for sake of completeness.

Considering the table in its set-up position as shown in Fig. 1, and desiring it to be folded, the clamps 28 are released as by lifting the clamp handles, thus freeing the ends of struts 26 and 27, after which the leg assembly including legs 22 and 23, brace 25, the struts, etc., may be rotated as a unit, in a counter clockwise direction (Fig. 3) about the pivots 24. Such rotation is carried through substantially three-fourths of a revolution, or until the legs 22 and 23 are brought into substantial parallelism with the rails 5 and 6, with the brace 25 substantially overlying the side rail 9. The struts 26 and 27 being free to rotate about the brace 25, are further rotated in the opposite direction, into substantial parallelism with the legs 22 and 23 and hence also with the end rails 5 and 6, after which the table lies substantially flat, (Fig. 2), so as to occupy a minimum space enabling it to be readily stored or compactly contained pending future use. When the table is folded the clamps 28 may be rotated about their pivots to the position shown in Fig. 2, and clampingly actuated to engage adjacent projections 29 on the end rails, thus effectively securing the device in folded position.

While the operation of folding the table has been described by reference to a movement of the leg structure relative to the nor-

mally horizontal supporting or table portion, the leg structure may obviously be kept stationary and the table portion rotated within and between the legs 22 and 23 to produce the same result. An advantage, upon folding, will be observed when it is considered that upon rotating the parts of the table into folded relation, the tab 18 forming pockets 19 will be brought, usually without separate effort, to such position that it immediately overlies the upper working surface of the table, for example the cover 10, the parts being in such relation that the pockets 19 fall between the tab 18 and the cover 10 in a manner to conceal and protect the contents of the pockets.

It will appear from the preceding description of parts and arrangement of the device that it has been designed throughout with a view of combining maximum adaptability and utility with a structure of unusually light weight and compactness. The device of the present showing has been constructed as a bathing and dressing table for infants and children weighing up to thirty-five pounds. On this basis, the device provides a safety factor of at least four, being ample to support without danger of breakage the weight of the normal adult of 140 to 150 pounds.

The provision of a flexible supporting surface consisting primarily of the canvas cover 10, has been found to be of particular advantage in that it enables ready replacement and laundering of this element. The provision of a cover of double thickness, the thicknesses thereof consisting respectively of the cover 10 and the auxiliary cover 16 which may be of rubber, will be noted as of obvious advantage in that, for purposes of bathing, the rubber cover may be removed or rolled to occupy only one edge of the operating surface. During the process of bathing, the canvas cover 10 will be, of course, depressed somewhat by the weight of the infant so as to bring one or more of the drainage apertures 13 near the lowest portions of the cover, which provision renders the table convenient as a support for shower bathing purposes. The provision of the auxiliary cover 16 of waterproof material, provides a surface which may be kept dry and laid over the previously moistened cover, so that the infant may be dried and dressed on the same support, to the end of minimizing lifting and transfer steps.

The recited provision for supporting the table primarily from the outside hand rail of the tub and by a vertical wall portion on the opposite side of the tub, has been found to be of particular utility, since in some instances the inner side of the tub may be embedded in the wall and consequently not available for supporting a table having the usual legs on its opposite sides.

I claim:

1. A table appliance for use with bath tubs and the like, including a frame, positioning means extended substantially transversely from the frame, a leg structure pivoted at one extremity to the frame, and combined means for selectively positioning the leg structure with respect to the frame, and selectively spacing the free extremities of said positioning means and leg structure.

2. A table folding appliance for use with bath tubs and the like, including a frame of substantially fixed dimensions, and leg portions pivoted to said frame and arranged for rotation between opposite sides of the plane of the frame as the pivotal portions are moved between their normal or operative, and their folded positions.

3. A table appliance having a normally horizontal frame portion and a unitary leg structure pivoted to each other for relative rotation about the plane of the frame and arranged for engagement with supporting surfaces disposed substantially at a right angle to each other, and means for adjusting the angularity of said frame and leg structure to compensate for differences in horizontal distances between the supporting surfaces.

4. A table appliance for use with a bath tub, including a frame and leg portions for horizontal disposition above the tub, a leg portion pivotally secured to the frame, and combined means for securing the pivoted leg portion in adjusted angular relation to the frame, and for adjusting the distance between extremities of the horizontal and pivoted leg portions.

5. A table appliance adapted for use with bath tubs and the like, including a framed supporting portion, fixed leg portions extending substantially parallel to the framed portion, a leg structure pivotally associated with the framed portion, and means for adjusting the width of the appliance between leg extremities, said means including an element engaging said leg structure near the free extremity thereof, and for selectively engaging the framed structure at selective distances from the point of pivotal connection of said leg structure.

6. In a device adapted for use in combination with bath tubs and the like, a supporting frame of fixed dimensions, a leg structure pivoted near one side of said frame, a brace pivoted near the free end of said leg structure and a clamp associated with said brace and arranged for engaging the frame structure at selected distances from the point of pivotal engagement of the leg structure.

7. A foldable table appliance for bath tubs and the like, including a frame adapted as a support in horizontal position, a leg structure pivoted to the frame near one side thereof, a brace member pivoted to the leg struc-

ture at one end, a clamping device pivotally secured to the opposite end of said brace member, and means forming a longitudinal seat on said frame for engagement by said clamping device.

8. A foldable table appliance for bath tubs and the like, including a table frame of fixed dimensions having horizontal legs, a single, unitary normally depending leg structure, one end of which is pivotally connected to the frame, means for clampingly adjusting the angular relation of the leg structure to the frame and the distance relation between the extremities of the horizontal and the depending legs when the appliance is in operative position.

9. A foldable table appliance for bath tubs and the like, including a table frame of fixed dimensions having horizontal legs, a normally depending leg structure, one end of which is pivotally connected to the frame at one side thereof, and means for clampingly securing the leg structure to the frame when the appliance is in operative position whereby to alter the distance between the extremities of the horizontal and the depending legs, said securing means further adapted for securing the leg structure in substantially parallel adjacency to the frame when the device is in folded position.

10. In combination with a folding table appliance for use with bath tubs and the like, a frame of fixed dimensions, a leg structure pivoted thereto, clamping means carried by the leg structure and adapted for engaging the frame, with the leg structure in depending relation to the frame, and further adapted for clampingly engaging the frame to secure the attachment in folded position.

11. A folding table for use with bath tubs and the like, including a frame, a leg portion pivoted to the frame and normally disposed in depending relation thereto, said leg portion being adapted for rotation from one side of the frame in operative position, to the opposite side of the frame when in folded position, and means for detachably positioning the leg portion on either side of the frame.

12. A foldable bathing and dressing table adapted for use with bath tubs and the like, the table including a normally horizontal frame portion having end rails extended in the plane of the frame to form horizontal legs, side rails on said frame, a plurality of detachable flexible coverings supported between said side rails, separate means for attaching said coverings to the frame, a pair of legs pivoted at opposite ends of the frame and arranged for rotation about an axis extending through the plane of the frame and at one side of its median line, said legs being provided at their lower extremities with arculate tub-rail engaging seats, a pair of braces, each pivotally connected to one of said pivoted legs, clamps pivotally connected with

the free ends of said braces, a longitudinal projection upon the under surface of each end rail of the frame structure and adapted for selective engagement by the corresponding 5 clamp, the pivoted legs having a brace extending therebetween whereby such legs are adapted for rotation as a unit, from depending position on one side of the frame when the device is in operative position, to a relation of substantially parallel adjacence with the opposite side of the frame when the attachment is folded for storage and the like.
